ON LINE. 5-5. FIG. 4.

A technical line drawing of a mechanical assembly, likely a component of a printing press. The drawing shows a base structure with various parts labeled with numbers. Key features include a central vertical column with a circular base (labeled 53, 23, 52, 26, 27, 30, 49), a horizontal beam with a central opening (labeled 55, 54, 25, 24, 23), and a side panel with a hinged door (labeled 59, 58, 57, 44). The entire assembly is shown in a perspective view, with some parts in cross-section to reveal internal details. The drawing is signed 'J. J. 91' in the top right corner.

UNITED STATES PATENT OFFICE.

JOHN FRITSCHE AND JOSEPH C. HADIK, OF PHILADELPHIA, PENNSYLVANIA; SAID HADIK ASSIGNOR TO SAID FRITSCHE.

VENDING MACHINE.

Application filed June 25, 1921. Serial No. 480,339.

To all whom it may concern:

Be it known that we, JOHN FRITSCHE, a citizen of the United States, residing in Philadelphia, county of Philadelphia, State 5 of Pennsylvania, and JOSEPH C. HADIK, a citizen of the United States, residing in Philadelphia, county of Philadelphia, State of Pennsylvania, have invented a new and useful Vending Machine, of which the following is a specification.

Our present invention relates to a novel construction and arrangement of a vending machine which has been especially designed to vend towels, although as is apparent, it 15 is not limited to such use and can be employed in all cases wherein it is desired to vend articles in package form or where the articles can be strung on a supporting element.

20 In case towels are to be vended, they are discharged into a position accessible to the intending user for temporary use only, but if desired they can be discharged in such a manner that the purchaser is free to take 25 them away with him, and the same of course holds true in connection with any other desired article which is to be vended.

With the above in view our invention in its broad and generic scope, comprehends a 30 novel vending machine, which is preferably coin or check controlled and wherein is employed a novel construction of a vending cabinet, novel means for supporting the articles to be vended within the cabinet; novel 35 means for effecting the delivery of an article into a position accessible to the purchaser, novel means for preventing the removal of more than one article at a time, novel means for rendering it necessary that the article 40 delivery mechanism move its full stroke in order to effect the delivery of an article, and novel means for rendering the vending mechanism inoperative in case the articles have all been vended and in case the proper 45 check or coin has not been deposited in the machine.

It further comprehends novel means for vending a plurality of articles on the deposition of a check or coin, one of said articles 50 being of a liquid nature.

It further comprehends a novel construction of a vending machine wherein the articles to be vended are given a lateral movement within the vending machine and then

released so that they are permitted to drop 55 to the bottom of the delivery chamber, which at such point is cut away to form an opening into which the purchaser can reach in order to remove the article purchased for temporary or permanent use from the machine.

It further comprehends a novel construction of a towel supporting and retaining member, and a novel construction of a manually actuated towel or article delivery 65 mechanism co-operating therewith.

Other novel features of construction and advantage will hereinafter more fully appear in the detailed description of the invention and the appended claims.

For the purpose of illustrating our invention, we have shown in the accompanying drawings a typical embodiment thereof which is at present preferred by us, since said embodiment will be found in practice 70 to give satisfactory and reliable results. It is, however, to be understood that the various instrumentalities of which our invention consists can be variously arranged and organized and that our invention is not limited to the precise arrangement and organization of these instrumentalities as herein shown and described.

Figure 1 represents, in perspective, a vending machine, embodying our invention.

Figure 2 represents a section on line 2—2 of Figure 1.

Figure 3 represents a section on line 3—3 of Figure 1.

Figure 4 represents, in front elevation, 90 a portion of the machine with the doors in their open position.

Figure 5 represents a section on line 5—5 of Figure 4.

Figure 6 represents a section on line 6—6 95 of Figure 5.

Figure 7 represents a section on line 7—7 of Figure 6.

Figure 8 represents a bottom plan view of the article delivery mechanism.

Figure 9 represents an end view of a portion of the construction seen in Figure 8.

Figure 10 represents a section on line 10—10 of Figure 4.

Figure 11 represents in elevation a portion of one of the doors, showing more particularly the manner in which the coil slot is closed.

Figure 12 represents, in section, a plurality of towels, and a guide member employed to properly align the articles prior to stringing them on the article retainer.

5 Figure 13 represents, in sectional elevation, a plurality of the towels, with the article retainer and the article aligning member in the positions they assume during the placing of the articles on the article retainer.

10 Similar numerals of reference indicate corresponding parts.

Referring to the drawings.

1 designates a vending machine embodying our invention. The vending machine is 15 provided with a lower cabinet 2 having an open top 3 thereby forming a chamber to receive the articles which have been temporarily used. The lower cabinet 2 is provided on the front with angles 4 and the rear angles 5 are secured thereto in any desired manner. The rear angles 5 carry at their upper ends the article receiving cabinet or casing 6 which contains the articles which are to be vended. This article receiving 20 cabinet 6 is secured to the rear standards 5 in any desired manner, for example, by riveting.

The article receiving cabinet 6 for the articles which are to be vended is provided with 30 a door 7 hinged thereto at 8 and with a door 9 hinged thereto at 10. When these doors are opened, the interior of the cabinet is readily accessible for the insertion of new articles to be vended or for inspection or re- 35 pair of the operating mechanism, it being seen that the coin controlling mechanism is carried by the door 9. The top, bottom, rear end and sides of the cabinet 6 are closed. The door 7 is cut away in order to form an 40 article delivery opening 11 and the door 9 in proximity to such opening is provided with a guard 12 which preferably extends beyond the front walls of the doors.

The door 7 is provided with an actuating 45 handle 13 exterior of the cabinet and operatively connected with locking bars 14, the lower of which is adapted to engage with the inner face of a flange 15, and the upper bar of which is adapted to interlock with a cross 50 bar 16 which contributes with the upper flange 17 to form a slot 18. The door 7 is provided with a portion 19, see the left-hand portion of Figure 4, which overhangs the door 9 when the latter is closed, so that when 55 the lock 20 is actuated to lock the door 7 both of the doors 7 and 9 will be retained in locked position. The article receiving cabinet 6 is provided with an article receiving chamber 21 which at its lower end is provided with an upwardly extending guard 22 in the form of a plate carried by the bottom 60 and rear walls of the cabinet 6.

The article retainer.

65 The article retainer consists of a longi-

tudinally extending bar 23 having a slot 24 extending longitudinally through it and opening through its top thereby forming the side walls 25 which are provided with notches or cut out portions 26 which at their forward ends form shoulders 27. The forward end of the article retainer 23 is provided with the downwardly and forwardly inclined terminal 28 which, as illustrated, is apertured to receive one end of a cable 29 secured thereto in any desired manner, for example, by means of a pin 30. The cable 29 passes through the article delivery opening 11 and into the chamber of the article container 2 for the used articles, and then passes up through an opening in the bottom of the article receiving cabinet 6, see more particularly Figure 4, and is secured therein by means of a pin or its equivalent 31. It will of course be understood that the cable 29 may be omitted in case a permanent sale of the article is to be made instead of a sale of the article for temporary use only.

For the purpose of illustrating one manner in which our invention can be employed 90 in practice, we have shown it as adapted to vend towels 32 which are reinforced by means of the grommets 33, which are strung on the article retainer 23. In order to accomplish this, the door 7 has pivotally supported at 34, see Figure 4, a smooth bar 35 which can be swung outwardly when the door 7 is opened, and the article retainer 23 brought into register with it, as will be understood by reference to Figure 13, so that 95 the towels can be readily slid into position on such article retainer, it being understood from Figure 12 that the articles are first preferably assembled on the smooth bar 35 which acts as a guide bar.

The article retainer 23 at its rear end, see Figure 6, is received in an aperture 36 in a block 37, secured in any desired manner to a wall of the article receiving cabinet 6.

The bar forming the article retainer 23 is secured in position by means of a screw 38, see more particularly Figure 7, which is in threaded engagement with the block 37 and is provided with a handle 39, whereby 100 it may be readily actuated to effect the locking into position or the unlocking therefrom of the bar 23.

In order to provide an additional support for the bar 23 so that it cannot become 105 loosened or bent out of shape by a careless or malicious operator pulling on the cable 29, we provide a supporting member 40 in the form of a plate pivotally supported at 41 to the rear wall of the article receiving 110 cabinet 6 and provided with a spring 42 which tends to retain it against a face of the angle 43, so that it will open in the direction in which an article is to be moved when removing it from the article retainer. 115 120 125 130

This supporting member 40, as best seen in Figure 5, extends beneath the article retainer 23.

Article removing mechanism.

The top wall of the article receiving cabinet 6 has connected therewith a bracket 44, see Figure 6, through which passes a bar 45, the rear end of which is received in a plate 46 forming a support for the block 37. The bar 45 is secured to the bracket 44 by means of a nut 47. 48 designates an article removing member which is in the form of a plate or slide slidable on the bar 45, and its forward end is slidable in the slot 18 and upon the cross bar 16. The plate 48 has an outwardly extending portion which is deflected to form a grasping handle 49, which as will be understood by reference to Figures 1 and 5, extends exteriorly of the article receiving cabinet 6. The plate 48 is provided with a clip 50, see Figure 6, which engages the underface of the bar 45 which is preferably polygonal in cross section.

The article removing member 48 has pivoted to it at 51, see Figure 6, a lever 52 which is provided at its forward end with a hook 53 and at its rear end with a pawl or detent 54. The lever 52 is acted upon by a spring 55 interposed between the plate 48 and the lever 52 on the side of its fulcrum 51 which carries the pawl 54, so that the tendency of the spring 55 is to move the pawl 54 into engagement with the wall of a recess 26 of an article retainer 23. The lever 52 is provided with an upward extension 56 which contacts with the plate of the article removing member 48 to limit the movement of the lever 52 in one direction. The bracket 44, see Figure 5, carries a cam block 57 having the rearwardly and upwardly inclined face 58 which is provided with a slot 59 to receive the lever 52 when it is in its initial position at the right hand end of the stroke of the article removing member 48. The plate 48 of article removing member has pivoted to it, at 60, a lever 61 having a tail piece 62 which contacts with the plate 48 to limit the rocking movement of the lever 61 in one direction, a spring 63 being provided interposed between the plate 48 and the lever 61. The lever 61 is provided with a plurality of shoulders 64 and has the underface of its forward end inclined. The plate 48 also carries a cam 65 having the reversely inclined cam faces 66 and 67, respectively. If desired the plate 48 may be provided 60 with the antifriction rollers 68.

Mechanism for preventing the purchase of an article when the machine is empty.

In order to prevent the operation of the machine when the last article has been

vended, we provide means for preventing the insertion of a coin into the machine through the coin slot 131 in the door 9. 70 designates a lever, see more particularly Figure 7, which is pivoted at 71 to the block 37 which supports the article retainer, so that it has a rocking movement in a lateral direction. The lever 70 has pivoted to it, at 72, an arm 73 which is maintained in its downward position by means of a spring 74, one end of which is connected to the lever 70 while its opposite end bears against the free end of the arm 73 to retain such arm in the first recess 26 of the article retainer 23, see also Figure 6. The last towel to be vended is 80 engaged by the hook 53 and the inclined face 75 passing under the arm 73 raises it out of engagement with a shoulder 27 of a recess 26 of the article retainer 23, so that a spring 76, see Figure 5, will cause 85 the rod 77 on which it is mounted and the lever 70 to which such rod is connected to move towards the left. The spring 76 is interposed between a set collar 78 and an apertured guide bracket 132, see Figure 4, 90 through which the rod 77 passes. The free end of the rod 77 is bent laterally and downwardly to form a hook 79, see Figure 11, which extends into a slot 80 of a plate 81 which is adapted to cover and uncover the 95 coin slot 68, see more particularly Figure 1. A spring 82, see Figure 4, has one end connected to the plate 81 pivotally connected to the door 9, and its opposite end is secured to a stationary portion of the machine such as, 100 for example, the door 9, so that the tendency of the spring is to move the plate 81 and to retain it in such position that the coin slot 68 will be uncovered. When, however, the plate 81 is actuated by the rod 77 upon the release 105 of the lever 70, the coin slot 68 will be closed, as is apparent.

The coin controlling mechanism.

Our present invention is preferably coin controlled in order that the purchaser at the time of purchase will deposit the proper amount in the machine. The coin if of the proper denomination is inserted through the coin slot 68 and, if of the proper dimension, 110 passes through the coin chute 83, see Figure 4, and into a coin retainer 84. One side 129 of the chute 83 is pivoted and acted upon by a spring 130 which tends to retain the pivoted side in its closed position.

The coin retainer 84 when in position for operating has the bottom of the aperture through it closed by means of a coin stop 85 which, as illustrated in Figure 4, consists of an angle guided in a bracket 86 and having a shoulder forming recess 87 in its upper face. One end of the stop 85 is pivoted at 88 to a lever 89 which is pivoted at 90 to a plate 91 secured to the door 9.

92 designates the actuating handle extend-

ing exterior of the door 9, see Figure 1, and connected at its inner end to a cam 93, see Figure 4, the lower end 94 of which is adapted to enter the coin retainer 84 and press downwardly on the coin to effect the release of the coin stop 85. The cam 93 has its upper end adapted to rock a lever 95, see Figure 4, which effects the opening of the pivoted side 126 of the coin chute 83. The cam 93 has connected to it one end of a spring 96, the opposite end of which is connected to the plate 91, and the plate 91 has also connected to it one end of a spring 97, the opposite end of which is connected to the stop 85, which also acts as a detent. The lever 89 has connected to it an upwardly extending arm 98 which passes through a bracket 99, and its upper end terminates in a hook or projection 100, see Figure 4. The arm 98 also carries a roller 101 with which co-operates the inclined cam faces 65 and 67 of the cam 65.

The lever 89 automatically controls the vending of a measured quantity of liquid such as, for example, liquid soap, and for this purpose it has pivotally connected to it at 102 a lever 103, one end of which moves in the path of a stop 104 carried by the lever 89, and one end of a spring 105 is connected to the pin 104 while its opposite end is connected to the lever 103.

The liquid vending mechanism.

The lever 103 on its movement in one direction actuates a bell-crank lever 106, see Figures 4 and 10. One end of this lever 106 bears against the under face of a cap nut 107 carried by a valve stem 108 which is guided in the liquid container 109. The valve stem 108 carries at its lower end a valve head 110 which controls the outlet port 111 of the liquid container 109. A spring 112 is interposed between the valve head 110 and the top wall of the casing of the liquid container 109. The valve head 111 carries a plunger 113 which extends into the chamber 114 of the measuring cup 115 which forms a part of a valve casing 116 which has a discharge pipe 117 leading to the main discharge outlet 118 for the liquid to be vended. The valve which controls the discharge of liquid from the measuring chamber 114 to the main liquid discharge outlet 118 is in the form of a spring pressed plunger 119 having a groove 120 which can be brought into register with the pipe 117 and the discharge outlet 121 from the measuring cup 115.

For the purpose of receiving the valve 119, the valve casing 115 is apertured, as at 122, and a spring 123 is provided interposed between the valve plunger 119 and a cap 124 in threaded engagement with the valve casing 115. A strap 125 connected with the door 9 engages the nut 124, as

will be best understood by reference to Figures 4 and 10, so that the valve mechanism is properly braced. The coins passing from the coin retainer pass into a money box 126, see Figure 4, and if a coin is retained in the coin chute it passes therefrom, when the pivoted side 129 is opened, into a return chute 127 which is accessible to the intending purchaser through the aperture 128 in the door 9.

The operation of our novel vending machine will now be readily apparent to those skilled in the art to which this invention appertains and is as follows:

The articles, for example, the towels 32, are placed on the guide and aligning rod 35 and the article retainer 23 is then inserted through the grommets 33 as will be understood by Figures 12 and 13. The article retainer is then removed from the aligning 85 and guide bar 35, which is then swung into the position seen in Figure 4. The article retainer is then placed in the position seen in Figures 4 to 7 inclusive, its inner end extending into the aperture 36 in the block 37, in which it is locked by actuating the handle 39 to rotate the screw 38. The locking arm 73 engages the walls of the first recess 26 in the article retainer 23, as seen in Figure 6. The articles are now strung on the article retainer and the article removing member 48 and its adjuncts are in the position seen in Figure 4, at the right-hand upper portion of the chamber 21. The supporting plate 40 rests beneath the article 100 retainer 23. The cable 29 if employed passes through the delivery opening 11 and is then passed through the bottom of the article receiving cabinet 6 and secured in position by means of the cotter pin or other fastening device 31. The door 9 is first closed and then the door 7 and the door 7 is locked by a key, thereby effecting the locking of both doors. It will be understood that prior to the locking of the doors the liquid container 109 has been filled with the liquid which is to be vended. As the article removing member 48 is moved rearwardly into the position seen in Figure 4, the cam 65 will ride beneath the roller 101 thereby 110 raising the arm 98 and rocking the lever 89, causing a shoulder of the recess 87 of the stop and detent lever 85 to interlock with the bracket 86 to effect the resetting of the locking mechanism. The machine is 115 now ready for operation. The operator places a coin of the proper denomination in the coin slot 68, and the coin passes through the coin chute 83 into the coin retainer 84 in which it is arrested by the stop 85, see 120 more particularly Figure 4. The intending purchaser now rotates the handle 92 in the proper direction to rock the cam 93, thereby causing the lower end 94 to press downwardly on the coin which is resting on the 125 door 9.

stop arm 85. This downward pressure moves the free end of the arm 85 downwardly thereby releasing it from the bracket 86, and the spring 97 causes the stop arm 5 85 together with the lever 89 which carries it to swing to the left of the position seen in Figure 4. This causes the stop arm 98 to be drawn downwardly so that the hook portion 100 is out of the path of the catch 10 61, see also Figure 9, so that the article removing member 48 is released and free to operate. As the lever 89 swings to the left of the position seen in Figure 4, the pawl 15 103 rocks the lever 106 to cause the valve stem 108 and its valve 110 to be raised, thereby permitting the measuring chamber 114 to be filled with liquid from the liquid container 109. The cam 93, see Figure 4, is operatively connected to the lever 95 to open 20 the pivoted side 129 of the coin chute 83 when the handle 92 is rotated in a direction to release the stop arm 98 from its engagement with the lever 61 carried by the article removing member. The purchaser now 25 takes hold of the grasping handle 49 of the article moving member 48 and moves it to the left its full stroke, and as it reaches the limit of its forward travel the hook 53 will pass into and lock with a grommet 33 of 30 a towel 32. This causes the lever 52 to be rocked on its fulcrum against the action of the spring 55, so that the pawl or stop member 54 is lifted out of engagement with a shoulder 27 of the article retainer 23. The 35 operator now moves the article removing member 48 rearwardly, carrying with it the lever 52 and the article which it has picked up, and as the pawl or stop 54 comes in contact with the inclined face 58 it is moved 40 upwardly so that the article which has been purchased and removed is released and drops down the inclined terminal 28 into the chamber 21 in proximity to the delivery opening 11. If the cable 29 is employed, the 45 article is retained on such cable, and, after use, drops into the lower cabinet 2 for the used article. It will be seen that the article removing member 52 is slidably in and guided by the article retainer 23 and is also 50 received in the groove 59 of the cam block 57, so that during its movement it is at all times properly guided. If the purchaser desires to obtain the liquid which he has purchased he pushes in the valve plunger 119, 55 so that the liquid will be delivered to him from the main liquid discharge outlet 118.

The return of the article removing member 48 to its initial position at the right hand end of its travel causes the cam 65 to 60 move in the path of the roller 101, see Figure 4, thereby raising the stop arm 98 into position to engage one of the shoulders 64 see also Figures 8 and 9 and at the same time the lever 89 is rocked, see Figure 4, to 65 cause the stop arm 89 to be moved into po-

sition beneath the coin retainer 84 and to interlock with the bracket 86 so that the machine is set for another operation.

It will be apparent that, if a person could reach an implement through the delivery 70 opening 11 so as to take hold of an article, the article could not be removed in this manner, since it will engage with a shoulder 27 on the article retainer 23 to prevent such removal. When the last article is removed from the machine, it will be seen that the forward movement of the article removing member 48 will cause the inclined face 57 to raise the arm 73, see more particularly Figures 6 and 7, thereby releasing such arm 80 from its engagement with the article retainer 23, and the spring 76 will cause the lever 70 to rock on its fulcrum, thereby causing the plate 81 to be moved into such position that the coin slot 68 will be covered, under which condition it is impossible to insert a coin into the machine to effect the release of the article removing mechanism.

In the foregoing description, we have described the operation as it takes place when the articles are sold for temporary use only. If the articles are to be sold for permanent use, so that they are to be carried away by the purchaser, the operation is the same except that the cable 29 is dispensed with or has its free end disconnected from the machine.

It will be seen that the article removing mechanism is constructed in such a manner 100 that the article removing member cannot be returned to its initial or filling position unless it has been given its full stroke on its forward movement so that it will engage with and remove an article, since otherwise 105 a stop or pawl on the article removing lever will engage with the rack formed by the recesses in the article retainer 23.

The articles to be vended are stored in the same chamber in which they are delivered, and the articles are supported on a longitudinally extending retaining bar, which is constructed in such a manner that when the articles are moved laterally along said bar they will drop by gravity and their 110 own weight into a position accessible to the purchaser.

The reason for employing a plurality of shoulders 64 on the locking member 61 is to cause the manually actuated slide or plate 115 to be positively locked as otherwise by a very delicate operation it might be possible for the intending purchaser to move the article removing member to such a position that the first towel would be released before the 120 article removing member was locked and the article removing member would then be again moved forwardly to effect the removal of a second article or towel so that one could obtain two articles for the price of one. It 125 130

will of course be understood that if the parts are properly proportioned and arranged a single locking shoulder can be employed on the locking member 61 and it is not necessary 5 in all cases to employ a plurality of such locking shoulders.

It will now be apparent that we have devised a novel and useful construction of a vending machine which embodies the features of advantage enumerated as desirable 10 in the statement of the invention and the above description, and while we have, in the present instance, shown and described an embodiment thereof which will give in practice satisfactory and reliable results, it is to 15 be understood that such embodiment is susceptible of modification in various particulars without departing from the spirit or scope of the invention or sacrificing any of 20 its advantages.

Having thus described our invention, what we claim as new and desire to secure by Letters Patent; is:

1. In a vending machine, a cabinet having 25 a chamber within which the articles are stored and within which they are delivered, an article retainer in the form of a rack on which the articles are individually locked, a manually actuated article removing member 30 slidable in said casing to effect the release and removal of an article from said rack, and means to lock said article removing member in its initial position and to effect its release therefrom.

35 2. In a vending machine, a cabinet having a chamber within which the articles are stored, an article retainer in the form of a rack on which the articles are individually locked, and a manually actuated article removing member adapted to interlock with 40 said rack and to be released from said rack when in engagement with an article.

45 3. In a vending machine, a cabinet having a chamber within which the articles are stored, an article retainer in the form of a rack on which the articles are individually locked, a manually actuated article removing member adapted to interlock with said rack and to be released from said rack when 50 in engagement with an article, and means to actuate the article removing member to release an article therefrom as the article reaches the end of said retainer.

55 4. In a vending machine, a casing having a delivery opening, an article retainer supported at one end in said casing and having means to prevent the removal of articles therefrom, an article removing member slidable laterally in said casing and having 60 means to disengage an article from said retainer, and means to effect the release of an article from said article removing member.

5. In a vending machine, a cabinet having a chamber in which the articles are stored,

an article support positioned substantially 65 horizontally in said casing and on which the articles are normally locked, a manually actuated article removing member slidable laterally in said casing to bring an article into position to fall from said retainer, and 70 means to actuate said article removing member when it reaches the point at which the article is to be delivered from said retainer to release it from the article which it is removing.

75 6. In a vending machine, a casing having an article receiving chamber and a delivery opening, an article retainer within said casing and on which the articles are strung, an article removing member slidable laterally in 80 said casing and automatically interlocking with said retainer if arrested prior to the completion of its full stroke and released from its engagement with said retainer by its co-operation with an article thereon, and 85 means to effect the release of an article from said article removing member during its travel to permit the article to fall by gravity from said article retainer.

90 7. In a vending machine, a casing having an article receiving chamber and a delivery opening, an article retainer supported within said chamber, an article removing member co-operating with an article to carry it to the delivery end of said retainer, and a cam 95 in the path of which said article removing member travels to effect the release of an article from said member when it reaches the delivery end of said retainer.

99 8. In a vending machine, a casing having 100 an article receiving chamber and a delivery opening, an article retainer within said casing and with which the articles are normally individually locked, a manually actuated member having means to automatically lock 105 it in initial position, means to effect the unlocking of said locking means, and devices automatically actuated by said manually actuated member to render the machine inoperative when the last article on said article 110 retainer has been vended.

115 9. In a vending machine, a casing having an article receiving chamber and a delivery opening, an article retainer supported within said chamber, a manually actuated slide slidable longitudinally of said member, a lever pivotally carried by said slide to engage an article on said retainer and carry it to the delivery end of said retainer, and means in the path of said lever to automatically actuate 120 it when it reaches such delivery end to effect the release of an article therefrom.

125 10. In a vending machine, a casing having an article receiving chamber and a delivery opening, a manually actuated slide, an article retainer within said casing, a lever carried by said slide adapted to travel in and be guided by said retainer and having means to

interlock with said retainer, resilient means to cause such interlocking, said lever being unlocked from said slide when engaged with an article on said retainer, and a cam to effect the release of an article from said lever when an article reaches the delivery end of said retainer.

11. In a vending machine, a casing having an article receiving chamber and a delivery opening, an article retainer in the form of a grooved rack supported within said casing, a manually actuated slide, a lever carried thereby and adapted to travel in the groove of said rack and provided at one end with a hook and at the opposite end with a pawl to engage said rack, means to cause such engagement, said hook when engaged by an article being moved into a position to disengage said pawl from said rack, and means to effect the automatic release of an article from said hook when the article reaches the delivery end of said retainer.

12. In a vending machine, a casing having a chamber provided with a delivery opening, an article retainer in said chamber, a manually actuated slide laterally movable in said chamber, means carried by said slide to release and remove an article from said retainer and carry it to the delivery end of said retainer, and cam means to effect the release of an article from said means when the article has reached the delivery end of said retainer.

13. In a vending machine, an article retainer in the form of a grooved bar having shoulders on the wall thereof, and an aligning and guide member adapted to be inserted into said groove, whereby the articles can be strung on said article retainer without contacting with said shoulders.

14. In a vending machine, an article retainer in the form of a grooved bar having recesses in the walls thereof forming shoulders, and a second bar slidable in said grooved bar and having a wall extending above the shoulders, whereby articles can be strung on said bars without contacting with said shoulders.

15. As a new article of manufacture, the herein described article retainer comprising a bar having a groove opening through a wall thereof, the sides of said groove being recessed to form a series of shoulders extending longitudinally of the bar.

16. As a new article of manufacture, the herein described article retainer comprising a longitudinally grooved bar, the side walls of the groove forming a rack and the delivery end of said bar being downwardly deflected.

17. As a new article of manufacture, the herein described article retainer comprising a longitudinally grooved bar, the side walls of the groove forming a rack and the delivery end of said bar being outwardly de-

flected and provided with an aperture adapted to receive a cable.

18. In a vending machine, a casing having a chamber and a delivery opening, an article retainer within said casing and supported at one end, and on which the articles are independently locked, a movable member carried by said casing and extending beneath said retainer intermediate the ends thereof, means to effect the release and removal of an article from said retainer, and devices to render said means operative or inoperative.

19. In a vending machine, a casing having a chamber and a delivery opening, an article retainer within said casing, a bar supported in said casing, said casing having a laterally extending slot in a wall thereof, a manually actuated slide slidable in said slot and on said bar, a member movably carried by said slide to release a towel from said retainer and carry it to the delivery end thereof, and means to effect the release of an article from said member when the article reaches the delivery end of said retainer.

20. In a vending machine, a casing having a chamber provided with a delivery opening, an article retainer within said casing, a lever mounted in said chamber, a spring actuated arm carried by said lever and retained in its normal position by said retainer, means to effect the release and removal of an article from said retainer and to release said arm when the last article on said retainer has been vended, and means actuated by said arm when released to prevent the operation of said machine.

21. In a vending machine, a casing having a chamber provided with a delivery opening, an article retainer within said casing, and on which the articles are independently supported, a manually actuated slide, means carried thereby to effect the release of an article from said retainer and to move it to the delivery end of said retainer, means to release an article from said slide when the latter reaches the delivery end of said retainer, a locking member carried by said slide, and a stop in the path of said locking member to interlock therewith when said slide is moved to its initial or starting position.

22. In a vending machine, a casing having a chamber provided with a delivery opening, an article retainer within said casing, and on which the articles are independently supported, a manually actuated slide, means carried thereby to effect the release of an article from said retainer and to move it to the delivery end of said retainer, means to release an article from said member when the latter reaches the delivery end of said retainer, a locking member carried by said slide, a stop in the path

of said locking member to interlock therewith when said slide is moved to its initial or starting position, and a cam carried by said slide to move said stop into locking position when said slide is moved to its starting position.

23. In a vending machine, a casing having a chamber provided with a delivery opening, an article retainer within said casing, and on which the articles are independently supported, a manually actuated slide, means carried thereby to effect the release of an article from said retainer and to move it to the delivery end of said retainer, means to release an article from said member when the latter reaches the delivery end of said retainer, a locking member carried by said slide, a stop in the path of said locking member to interlock therewith when said slide is moved to its initial or starting position, a cam carried by said slide to move said stop into locking position when said slide is moved to its starting position, and means to effect the release of said stop.

24. In a vending machine, a casing having a chamber provided with a delivery opening, an article retainer within said chamber in the form of a grooved rack, manually actuated means to remove an article from said rack, and a bar carried by said casing and adapted to be received in the groove of said rack whereby articles can be strung on said rack without the rack portion interfering with such operation.

25. In a vending machine, a casing having a chamber and a delivery opening, an article retainer in the form of a bar extending laterally in said casing and having one end detachably mounted within said chamber, means to lock said bar in position, the terminal end of said bar being within said chamber, manually actuated means to effect the removal of an article from said retainer to its terminal end whereby it will drop by gravity to the bottom of said chamber in proximity to said opening through which latter it is removed by the purchaser, and a guard within said chamber in proximity to said opening to prevent an unauthorized person having access to the articles which have not been vended.

26. In a vending machine, a casing having a chamber, within which the articles are stored and also vended, an open side and a plurality of doors covering said side and one of which overlaps the other, one of said doors having an article delivery opening communicating with said chamber, an article retainer terminating within said chamber, manually actuated article removing mechanism slidable in said casing, and controlling mechanism carried by one of said doors to effect the locking of said article delivery

mechanism in its inoperative position and its release from its locked condition.

27. In a vending machine, a casing having a chamber, a portion of which is inaccessible to the purchaser and another portion which is accessible to the purchaser, an article retainer on which the articles are supported within the inaccessible portion of said chamber, a manually actuated member, and a spring actuated lever carried by said member and adapted to be interlocked with said article retainer by the action of said spring and to be released from said article retainer while said lever is engaged with an article on said article retainer.

28. In a vending machine, a casing having a chamber, a portion of which is inaccessible to the purchaser and another portion which is accessible to the purchaser, an article retainer on which the articles are supported within the inaccessible portion of said chamber, a manually actuated member, a spring actuated lever carried by said member and adapted to be interlocked with said article retainer by the action of said spring and to be released from said article retainer while said lever is engaged with an article on said article retainer, and means to actuate said lever to release an article therefrom.

29. In a vending machine, an article support, an article removing member slidably mounted and adapted to successively engage the articles and carry them to delivery position, and a stationary member co-operating with said article removing member to effect the release of an article therefrom when it reaches delivery position.

30. In a vending machine, an article support, an article removing member slidably mounted, guided by said support, and adapted to successively engage the articles and carry them to delivery position, and a stationary member co-operating with said article removing member to effect the release of an article therefrom when it reaches delivery position.

31. In a vending machine, a casing having an article receiving chamber, an article retainer in said chamber, an article removing member movably mounted relatively to said retainer and automatically interlocking with said retainer if arrested prior to the completion of its operative stroke and prevented from such interlocking if an article is being carried by it, and means to effect the release of an article from said article removing member.
